ELECTROMECHANICAL CLOCK

Oscar H. Dicke, New Bremen, Ohio

Application June 29, 1949, Serial No. 101,932

10 Claims. (Cl. 58—34)

1

This invention relates to clock mechanism for very accurately manifesting the passing of time including time-keeping mechanism which measures the passing of time irrespective of an alternating current cessation which is both automatically set and automatically regulated by alternating current of regulated frequency.

At present substantially all alternating current commercially generated has its frequency regulated so that its average frequency correctly manifests the passing of time. There are two shortcomings to such alternating current as a time keeping source. (1) This source of current at times fails; and (2) the frequency is not sufficiently constant to measure extremely short intervals of time since it is the average frequency and not the instantaneous frequency that correctly manifests the passing of time.

In accordance with the present invention it is proposed to employ clock mechanism which may be fairly well relied upon to keep accurate time when properly adjusted which is provided with regulating means by the manipulation of which the time keeping speed of the clock may be adjusted, to provide means automatically operated in accordance with the average frequency of an alternating current of regulated frequency to operate this regulating means to a position to cause said clock mechanism to correctly manifest the passing of time and to additionally provide means for at spaced time intervals setting the clock hands of such clock mechanism in accordance with the number of cycles of alternating current that have been supplied since the last setting operation.

Another object of the present invention resides in performing both of these functions with the same synchronous motor.

Another object of the present invention resides in performing the regulating function in a manner so that a regulating function that has once been performed is not interfered with as a result of an alternating current cessation.

Another object of the present invention resides in providing means to bring the synchronous motor operated mechanism back into chronological synchronism with the clock mechanism after each current cessation.

Another object of the present invention resides in providing setting means which does not interfere with the free and proper operation of both the clock mechanism and the synchronous motor operated mechanism.

Other objects, purposes and characteristics of the present invention will become apparent from

2

the following specification when considered in the light of the drawings in which:

Figs. 1 and 1a show one conventional embodiment of the present invention in a manner to facilitate description of the various mechanisms and their functions rather than the exact construction preferably used in practicing the invention.

Structure.—Referring to the drawings the main spring 10, which may be wound in any suitable way, drives the gear 11 which through its shaft 100 drives the pinion 102, which is in mesh with gear 101. Gear 101 through the medium of slip clutch 104 drives shaft 103 having secured thereto a gear 105 and a setting arm 135. A minute hand 136 is shown driven by a gear 99 driven by gear 105 at a one-to-one gear ratio. An hour hand 136a ($\frac{1}{12}$ R. P. H.) is driven by the gear 99 through the medium of the usual hour-hand reduction gearing shown. The gear 105 is also in mesh with gear 106 having the same number of teeth as gear 105. This gear 106 has secured thereto a cam 112 preferably of insulating material. This main spring gear 11 also drives the pinion 12 which is connected by shaft 9 to gear 13 in mesh with pinion 14. Pinion 14 through shaft 15 drives gear 16 in mesh with pinion 17 which through shaft 18 drives escape wheel 19.

The escape wheel 19, tends to oscillate the pallet 20. This pallet is pivoted at 21 and supports two laterally projecting pins 22 located on opposite sides of a flat leaf spring 23. This leaf spring 23 supports pendulum 24 and has its upper end secured to a preferably square threaded shank 25 which has its threads supported by the threads contained in the axial opening of a worm wheel 26. This worm wheel 26 is supported by and the shank 25 is guided in a fixed support 28. It is thus seen that the effective length of the pendulum 23—24 is changed as the worm wheel 26 is rotated. The worm wheel 26 is driven in one direction or the other (and at times remains stationary) by the worm 27 secured to gear 30. Gear 30 is at times driven by pinion 31, driven by friction wheel 33 through the medium of shaft 32. Another friction wheel 34 is pivotally supported in a spider 35 pivoted on a fixed pin 36 on which there is also pivoted a pinion 37 in meshed relation with a gear 34a secured to friction wheel 34. When electromagnet 40 is energized by alternating current (or direct current derived from such alternating current) the spider 35 assumes the position shown and holds the friction wheel 34 in driving

engagement with the friction wheel 33 against the tension of spring 39. When, however, this electro-magnet 40 is deenergized this spring 39 draws the friction wheel 34 out of engagement with the friction wheel 33.

The electro-magnet 40 is connected in multiple, or in series, if desired, with the synchronous motor SM so that if one of these electro-responsive devices is energized the other is also energized. The conditions under which these electro-responsive devices are energized will be pointed out hereinafter.

The pinion 37 is at times driven by the pinion 42 in meshed relation therewith, which pinion 42 is connected to worm wheel 44 through the medium of shaft 43. Worm wheel 44 is driven by worm 45 on shaft 46 which is, as by a pin 48, connected to the ring wheel or planet supporting wheel 47. This ring wheel 47 is provided with stub shafts, which have their axis arranged radially and on which are pivoted planet pinions 50. Two bevel gears 51 and 52 are pivotally supported on shaft 46. A worm wheel 53 is secured to bevel gear 51 and a worm wheel 54 is secured to or integral with bevel gear 52. Both of these bevel gears 51 and 52 are in meshed relation with planet pinions 50. From this construction it is readily seen that if worm wheels 53 and 54 are rotated at different speeds and in opposite directions the ring wheel 47 is rotated at a speed equal to the difference of the speed of rotation of worm wheels 53 and 54, and if rotated at the same speed the ring wheel 47 and shaft 46 remain stationary. As shown by the arrows, the worm wheels 53 and 54 are rotated in opposite directions, the worm wheel 53 being driven by the worm 60 cut into shaft 61 to which worm wheel 62 is connected and the worm wheel 54 by worm 70 on shaft 71. The worm wheel 62 is driven by worm 63 cut into shaft 64 having a worm wheel 65 secured thereto and driven by a worm 66 cut into shaft 15 of the escapement clock. Similarly the worm wheel 54 is driven in the opposite direction by worm 70 cut into shaft 71, driven by worm wheel 72, driven by worm 73 cut into shaft 74 of synchronous motor SM. The speeds of the shafts 14 and 100 and the gear ratios from these shafts to the worm wheels 54 and 53 respectively are such that the worm wheels 53 and 54 rotate at the same speed, and in opposite directions when the clock mechanism keeps perfect time and when exactly sixty cycle alternating current is applied to synchronous motor SM. When these worm wheels 53 and 54 and their associated bevel gears 51 and 52 rotate at different speeds the ring wheel 47 will rotate at the difference of the two speeds to thereby cause operation of the gear train between shaft 46 and pendulum adjusting worm wheel 26. These various gear ratios are such that if the clock mechanism gains one minute in 48 hours ($\frac{1}{2}$ minute per day) the pendulum will be lengthened so as to gain only one-half minute in 48 hours after 48 hours of operation. In other words the gear ratio is such as to make a half correction in 48 hours.

The synchronous motor SM also sets the clock hands 36 and 36a associated with the escapement clock mechanism. To perform this setting function the shaft 74 of the synchronous motor SM is provided with a pinion 121 which drives the gear 122 secured to shaft 108 supported in fixed bearings 88, 89 and 90. On this shaft is pivotally supported a sleeve 107 which supports gear 106 and slip ring 110. The shaft 108 sup-

ports a preferably square block 126 to which a leaf spring 127 is secured. The other or free end of this leaf spring supports a setting arm 125 so that the leaf spring 127 constitutes a spring bearing fulcrum. During operation of shaft 108 the setting arm 125 is urged against and rides against the fixed spiral cam 130, it being urged thereagainst by the spring 128. At the end of each hour, or other suitable time period as determined by the synchronous motor operated portion of the clock mechanism, the setting arm 125 snaps off of the leaving end of cam 130 and onto the starting end of this cam and in so doing causes the open V-shaped hammer, constituting two obliquely arranged arms 125a, to set the setting arm 125 to the proper chronological position if it does not already assume such position.

Each time that an alternating current cessation occurs the setting arm 125 will discontinue rotating at least so long as the current cessation continues. If it were to start rotating when alternating current flow is resumed it would not indicate the proper time insofar as the minutes within an hour is concerned. For this reason the synchronous motor SM and in turn the arm 125 is prevented from rotating until the shaft 108 manifests the same chronological condition as does shaft 103. This critical starting of the synchronous motor SM is accomplished by the snap action contact 113-114. The gear 106 which is in meshed relation with gear 105 supports a cam 112 having a beaked end 112a, both preferably of insulating material, at the end of which there is a flexible contact 113. To the shaft 108 is secured an arm 116, preferably of insulating material, having a projecting crank member supporting a spring contact 114 which is located to ride on the insulated cam 112 and beak 112a and which will when it reaches the end of the beak 112a snap by the end and momentarily engage the contact 113. This momentary engagement of contacts 113 and 114 occurs when the shaft 108 and the sleeve 107 assume the same chronological position about the axis of these elements.

On the sleeve 107 is secured a slip ring 110 which is connected by wire 123 to contact 113. Similarly the shaft 108 is provided with a slip ring 109 connected by wire 124 to contact 114. The contacts 113-114 constitute a pick-up circuit closer for synchronous motor SM, whereas the contact 120 associated with the magnetic circuit of this motor SM is closed only when the synchronous motor SM is energized and therefore this motor will continue to have its energizing circuit closed until an alternating current cessation occurs. The reference character A. C. signifies a source of alternating current having its frequency regulated so that its average frequency correctly manifests the passing of time. Attention is directed to the fact that the winding of motor SM is connected in multiple with the coil of electro-magnet 40. If desired this winding and coil may be connected in series. Also the contact 120 is a holding contact which is, as shown, closed in response to activation of the magnetic field of motor SM. If desired this contact 120 may be associated with the electro-magnet 40 and closed when the coil of this electro-magnet 40 is energized. When contact 120 is closed both the electro-magnet 40 and the synchronous motor SM are energized directly from the alternating current source, there being no other contacts in the energizing circuits, and they will both remain energized until a cessation

in the supply of alternating current occurs. When an alternating current cessation occurs both of these energizing circuits are broken by the opening of contact 120 and will remain broken even though the supply of alternating current is restored. It is only in response to the momentary closure of contacts 113-114 that the motor SM and/or the electromagnet 40 can be re-energized.

Operation.—Let us assume, for the purpose of discussion, that the escapement portion of the clock mechanism has the length of its pendulum so adjusted, presumably in the course of manufacture, so that it runs fast to an extent of one-half minute per hour (gains twelve minutes per day). Also, that the synchronous motor SM and electro-magnet 40 are both deenergized because the contacts 113-114 have not yet been momentarily closed since the alternating current source was wired to the clock mechanism. Let us also assume that the clock hands 136 and 136a indicate 11:58 p. m. the correct time and that the synchronous motor mechanism by its clock hand 137 indicates 11:59 p. m. One minute later, namely, when both the escapement portion and the synchronous motor portion of the clock mechanism indicate 11:59 p. m. the contact 114 drops off of the beak 112a down to the low portion of the cam 112 and in so doing this contact 114 momentarily engages the contact 113. This momentary engagement of these contacts 113 and 114 causes energization of motor SM and electro-magnet 40 and causes closure of contact 120 irrespective of whether this contact 120 is associated with the synchronous motor SM or the electromagnet 40. A pick-circuit is then closed from the source A. C. wires 151 and 152, slip-ring 109, wire 124, contacts 114 and 113, wire 123, slip-ring 110, wires 153, 154 and 155 winding of synchronous motor SM wire 156 back to the source A. C. Also, in multiple with wires 155 and 156 going to the synchronous motor SM are wires 155a and 156a extending to electro-magnet 40. As soon as contact 120 closes the pick-up portion of the circuit just traced and including contacts 113-114 is shunted out by a stick circuit branch including wires 157 and 158 and holding contact 120. The synchronous motor portion of the mechanism and including shafts 74 and 108 and gears 121 and 122 are now operating as well as gear 106 which was always operating. One minute later, namely at 12:00 midnight, the setting arm 125 snaps off of the leaving end of cam 130 and in so doing sets the escapement clock portion of the clock mechanism and including shaft 103, gears 99, 105 and 106 and clock hands 136 and 136a.

It should be observed that the gears 101 and 122 as well as the arms 116 and 125 on shaft 108 are not affected in any way by this setting operation by reason of slip clutch 104 and the idling of gear 106 on shaft 108. In this particular instant the setting arm 135 already assumed substantially the position mid-way between the two V-portions 125a of the setting arm 125 in that the accumulative error during one minute of operation is very small and little change in the positions of clock hands 136 and 136a took place. When the setting arm 135 is slightly toward one side or the other an effective setting operation will take place.

One hour later, namely at 1:00 a. m., as indicated by the synchronous motor clock-hand 137 the clock hands 136 and 136a indicate about 29 seconds past one o'clock in the morning. They 75

would have indicated about 30 seconds past one o'clock were it not for the fact that the escapement portion of the clock mechanism keeps slightly better time than it did formerly in that the pendulum 24 has been lengthened a little during the past hour. This was accomplished because worm wheel 53 rotated a little faster than worm wheel 54 and in so doing rotated the ring wheel 47 in a direction to lengthen the effective length of the leaf-spring 23, constituting part of the pendulum 23-24. In this connection it should be remembered that the electromagnet 40 was energized for the past hour and therefore held the friction wheels 33 and 34 in driving engagement so that the rotation of ring-wheel 47 was effectively transmitted, at a greatly reduced speed, to the worm wheel 23 directly above the pendulum. At this instant (1:00 a. m. alternating current time) the setting arm 125 snaps off of the leaving end of cam 130 and onto the starting end of this cam and in so doing sets the clock hands 136 and 136a backward to an extent of about 29 seconds, and both sets of clock hands now indicate 1:00 a. m. and correct time. Hour after hour, or any other suitable time period, this setting operation is repeated but in each case the escapement mechanism gains less than it did during the preceding hour. At midnight of the second day, namely forty-eight hours after the clock was set manually and wired to the commercial alternating current source of regulated frequency, the pendulum 24 has been lengthened to an extent where the escapement portion of the clock mechanism gains only fifteen seconds per hour instead of thirty. If we assume that no power failure occurs for another six-day period (eight days altogether and a fair assumption) the escapement clock will have been regulated toward correct time keeping to an extent where it only gains one and seven-eighths seconds per hour, but it still indicates correct time at the end of each hour by reason of being set periodically by the synchronous motor mechanism.

Let us now assume that at 12:01 a. m., at the beginning of the ninth day, an alternating current cessation occurs and that the cessation continues for 29 minutes. When at 12:30 a. m. power comes back on and alternating current is again available nothing in particular happens and so it could just as well have remained off a much longer time. Nothing happens because the alternating current that is available cannot reach either the synchronous motor SM nor the electromagnet 40. However, at 1:01 as manifested by the escapement clock the spring contact 114 snaps off of the end of the beak 112a and in so doing momentarily engages the contact 113 to thereby energize both the synchronous motor SM and the electro-magnet 40 after which both of these electro-responsive devices will remain energized through the medium of closed holding contact 120. Both the escapement portion and the synchronous motor portion of the clock mechanism now manifest the same time, both are however one and seven-eighths seconds fast because the escapement clock was gaining at the rate of one and seven-eighths seconds per hour during the hour when the synchronous motor SM was de-energized and at rest. That is, the time keeping quality of the clock was improved in four two-day periods to gains of 15 seconds, $7\frac{1}{2}$ seconds, $3\frac{3}{4}$ seconds and $1\frac{1}{8}$ seconds per hour. At 2:00 a. m. as manifested by the synchronous motor portion of the clock mechanism the clock

7
hands 136 and 136a were again set by the setting mechanism 125—125 but after such setting function the clock hands 136—136a are still one and seven-eighths seconds fast because the synchronous motor SM was started one and seven-eighths seconds before one hour had elapsed after the current cessation started. In other words, if a clock automatically regulated and periodically set in accordance with this invention is installed on a customer's premises extremely poorly regulated (say to gain 30 seconds per hour) it will be regulated to gain less than one second per hour ten days after the date of installation. If no alternating current cessation occurs in this time the clock mechanism will still indicate substantially correct time at the end of each hour and will indicate correct time within less than one second during each hour after the tenth day. If, however, a current cessation occurs at the end of the eighth day, as above assumed, the clock mechanism will have the same time keeping quality but the clock mechanism will be one and seven-eighths seconds fast for reasons above given.

The main spring 10 may be wound manually by the usual winding key and ratchet holding mechanism or may be wound automatically by any one of the various electric winding mechanisms well known in the art, or if desired may be wound by the synchronous motor SM through the medium of reduction gearing including a slip clutch.

It should be understood that the synchronous motor starting and the clock setting function is not necessarily performed on an hourly basis as specifically disclosed but may be performed on any desired time period basis. Also, other forms of mechanism than that shown may be used.

The exact gear reduction from the differential DF to the worm wheel 26 associated with the pendulum support 23 cannot be given because the screw pitch in the hole of the worm wheel 26 is a factor, as is also the normal speed of rotation of worm wheels 53 and 54 of the differential DF. The most accurate way of stating this gear ratio is to say that it is such as to cause the pendulum to change in length to an extent that its time keeping error will be corrected, that is, reduced fifty percent for each, say, forty-eight hours of regulation. This correction is purposely made extremely slow so that proper averaging of the alternating current frequency will result and also so that small variations in frequency will produce substantially no effect insofar as adjustment of the pendulum length is concerned. This phase of the automatic regulating feature of the present clock mechanism is more fully described in my prior application Serial No. 101,934 filed June 29, 1949, to which attention is directed. Stating it briefly the regulating function is carried out so gradually that the escapement mechanism will be adjusted to the average frequency and not so fast as to follow variations in frequency.

It should be understood that the timekeeping portion of the present invention is not necessarily an escapement pendulum clock but may be an escapement clock of the hair-spring balance-wheel type or may, in fact, be of any suitable construction so long as it has good time keeping qualities and provided that it may be regulated while in operation.

It should be understood that the setting feature of the present invention may be used separately from the regulating feature and vice versa.

Having thus shown and described only one

8
specific embodiment of the present invention it should be understood that the particular embodiment shown has been selected to facilitate a description of the underlying principles of the invention and how these principles may be carried out in practicing the invention; and that various changes, modifications and additions may be made in practicing the invention so long as these changes do not depart from the spirit or scope of the invention as defined by the scope of the following claims.

What I claim as new is:

1. Time manifesting apparatus comprising; clock mechanism including a gear train, a slip clutch, clock hands rotated by said gear train through the medium of said slip clutch, means for driving said gear train tending to drive it at excess speed, governing means for retarding the speed of operation of said gear train, regulating means for controlling the speed limit imposed by said governing means; a source of alternating current of regulated frequency so regulated that its average frequency correctly manifests the passing of time; a second gear train; a synchronous motor for operating said second gear train; means including one contact operated by said clock mechanism and a second contact assuming a position dependent on the position then assumed by said second gear train for at least momentarily connecting said synchronous motor to said source of alternating current when said second gear train and said clock hands manifest the same time; means including a holding contact for maintaining said synchronous motor connected to said source of alternating current when said synchronous motor has been once energized until a cessation of alternating current occurs; means controlled by said second gear train for periodically setting said clock hands to the same chronological condition as that manifested by the second gear train as permitted by said slip clutch, and means controlled jointly by said two gear trains for operating said regulating means to an adjusted position relatively slowly to cause said clock mechanism after a relatively long period to be adjusted to operate at a speed to cause said clock hands to correctly manifest the passing of time as manifested by the average frequency of said alternating current source.

2. Time manifesting apparatus comprising; clock mechanism including a gear train, a slip clutch, clock hands rotated by said gear train through the medium of said slip clutch, means tending to drive said gear train at an excessive speed, governing means for retarding the speed of operation of said gear train, regulating means to control said governing means; a source of alternating current having its frequency so regulated that its average frequency correctly manifests the passing of time; a second gear train; a synchronous motor for operating said second gear train; contacts assuming relative positions dependent on the relative positions assumed by said second gear train and said clock hands and closed momentarily when said second gear train and said clock hands assume the same chronological condition included in an energizing circuit for said synchronous motor; a holding contact for maintaining said synchronous motor in a closed circuit until a cessation of alternating current from said source occurs; means controlled by said second gear train for periodically setting said clock hands to the same chronological position as that manifested by said second

gear train as permitted by said slip clutch; and means controlled jointly by said two gear trains and in accordance with the difference of their speeds of rotation for operating said regulating means to an adjusted position relatively slowly to cause said clock mechanism after a relatively long period to operate at a speed to cause said clock hands to correctly manifest the passing of time as determined by the average frequency of said alternating current source.

3. Time manifesting apparatus comprising, clock mechanism provided with clock hands frictionally connected by a friction slip clutch to said clock mechanism, a source of commercial alternating current having its frequency regulated so that its average frequency correctly manifests the passing of time, synchronous motor mechanism including a synchronous motor energized from said source of alternating current for periodically setting said clock hands as permitted by said friction slip clutch so long as no current cessation occurs, means for preventing the restarting of said synchronous motor upon the restoration of the alternating current until at an instant one setting period after such current cessation started, and means for maintaining said synchronous motor energized until a cessation of such alternating current occurs.

4. Time manifesting apparatus comprising, clock mechanism including a time shaft, clock hands, a friction slip clutch for driving said clock hands by said time shaft, a source of alternating current having its frequency regulated so that its average frequency correctly manifests the passing of time, a synchronous motor at times connected to said source of alternating current, setting means controlled by said synchronous motor for periodically setting said clock hands as permitted by said slip clutch and only so long as no current cessation occurs, means for temporarily preventing the energization of said synchronous motor after a current cessation and reenergizing said synchronous motor after the termination of such cessation only at an instant when said clock mechanism manifests the same chronological condition as is manifested by said setting means, and means for maintaining said synchronous motor energized until a cessation of such alternating current occurs.

5. Time controlled mechanism comprising, a clock mechanism having a friction clutch and clock-hands frictionally connected to said clock mechanism by said friction clutch and provided with regulating means for regulating its speed of operation, a source of alternating current having its variable frequency regulated so that its average frequency correctly manifests the passing of time, a synchronous motor, a shaft driven by said synchronous motor and rotated at a speed of one revolution in a particular period of time as manifested by the average frequency of said alternating current source during such period of time, a shaft driven by said clock mechanism at a speed of one revolution in the same period of time but as manifested by said clock mechanism, contacts including contacts operated by said shafts and a holding contact for connecting said synchronous motor to said source of alternating current only when said shafts assume the same chronological position and maintaining it connected until and only until an alternating current cessation occurs, setting means controlled by the shaft driven by said synchronous motor for setting said clock-hands as permitted by said friction clutch periodically to the same chrono-

logical condition as manifested by the shaft driven by said synchronous motor, and means controlled jointly by said clock mechanism and said synchronous motor for operating said regulating means relatively slowly in accordance with the difference of the times manifested by said clock mechanism and said synchronous motor and after a relatively long period of time cause said regulating means to be adjusted to a condition to cause said clock mechanism to correctly manifest the passing of time as determined by the average frequency of said alternating current source over such relatively long period of time.

6. Time controlled mechanism comprising, clock mechanism including a friction clutch and clock-hands frictionally connected thereto by said clutch and provided with regulating means for regulating its speed of operation, a source of alternating current having its frequency regulated so that its average frequency correctly manifests the passing of time, a synchronous motor, a shaft driven by said synchronous motor and rotated at a speed of one revolution in a particular period of time as manifested by the average frequency of said alternating current source, a shaft driven by said clock mechanism at a speed of one revolution in the same period of time but as manifested by said clock mechanism when its regulating means is correctly adjusted, contacts operated respectively by the two shafts and connecting said synchronous motor to said alternating current source by being closed momentarily when said shafts assume the same chronological rotated position, holding contacts for maintaining said synchronous motor so connected until and only until an alternating current cessation occurs, setting means driven by the shaft driven by said synchronous motor for periodically setting said clock hands as permitted by said friction clutch, and adjusting means controlled jointly by said clock mechanism and said synchronous motor for adjusting said adjusting means relatively slowly in accordance with the difference of the times manifested by said clock mechanism and said synchronous motor and for operating said regulating means to cause said clock mechanism after a relatively long period of correction to correctly manifest the passing of time as determined by the average frequency of said alternating current source over said relatively long period, and means for rendering said last mentioned means wholly ineffective to adjust said adjusting means so long as said synchronous motor is deenergized.

7. Time controlled mechanism comprising, time lapse manifesting means driven from a local source of energy including a shaft rotated at a speed of one revolution in a predetermined period of time as measured by said means and including a friction clutch and clock-hands frictionally driven thereby, a source of alternating current of regulated frequency having its varying frequency so regulated that its average frequency over relatively long periods of time correctly manifests the passing of time, a synchronous motor, a shaft driven by said synchronous motor at a speed of one revolution in said predetermined period of time as manifested by the cycle passage of said alternating current, two contacts supported respectively by the two shafts for connecting said synchronous motor to said source of alternating current closed momentarily when said shafts assume the same chronological position of rotation, holding contacts for maintaining said motor so

11

connected so long and only so long as no alternating current cessation occurs, and setting means controlled by the shaft driven by said synchronous motor for periodically setting said clock-hands to the same chronological position as manifested by the shaft driven by said synchronous motor as permitted by said friction clutch.

8. Time manifesting apparatus comprising, mechanical time measuring apparatus, electrical time measuring apparatus including a self starting synchronous motor, and contact mechanisms for allowing the restarting of said synchronous motor after a current cessation only when said mechanical and said electrical time measuring apparatuses assume the same chronological condition, means for maintaining said synchronous motor energized until and only until a cessation of alternating current supplied to said synchronous motor occurs, and means governed by said electrical time measuring apparatus for setting said mechanical time measuring apparatus periodically.

9. Time manifesting apparatus comprising, mechanical time measuring apparatus, a source of alternating current having its frequency regulated so that its average frequency correctly manifests the passing of time, electrical time measuring apparatus including a self starting synchronous motor at times connected to said source, contact mechanisms for starting said synchronous motor only when said mechanical and said electrical time measuring apparatuses assume the same chronological condition, means for maintaining said synchronous motor energized until a cessation of alternating current supplied to said synchronous motor occurs, and means controlled by said electrical time measur-

ing apparatus for periodically setting said mechanical time measuring apparatus.

10. Time manifesting apparatus comprising, mechanical time measuring apparatus, a friction slip clutch, clock hands driven by said mechanical time measuring apparatus through the medium of said slip clutch, electrical time measuring apparatus including a synchronous motor, a source of alternating current of regulated frequency, contacts controlled respectively by said mechanical time measuring apparatus and said electrical time measuring apparatus and closed only when said mechanical time measuring apparatus and said electrical time measuring apparatus manifest the same time for initially energizing said synchronous motor from said source, holding contacts for maintaining a holding circuit for said motor closed until an alternating current cessation occurs, means controlled in accordance with the difference of the time integration measured by said mechanical and said electrical time measuring apparatuses for adjusting the rate of operation of said mechanical time measuring apparatus and acting relatively slowly so as to cause it to correctly manifest the passing of time as determined by the average frequency of said source applied to said synchronous motor, and means controlled by said electrical time measuring apparatus for periodically setting said clock hands as permitted by said slip clutch.
